UNITED STATES PATENT OFFICE

EUGENE C. KINNEAR, OF EVANSTON, ILLINOIS, ASSIGNOR, BY MESNE ASSIGNMENTS, TO THE LAKE ERIE CHEMICAL COMPANY, OF CLEVELAND, OHIO, A CORPORATION OF OHIO

VAULT-WALL-PROTECTING DEVICE

Application filed January 31, 1923. Serial No. 616,175.

This invention has for a principal object the provision of a protective device for preventing access to the interior of a vault or other depository in the event that the walls 5 are attacked to gain entrance, which now is one of the methods by which burglars force entrance to perpetrate thefts. As a means of accomplishing this result, the invention contemplates the employment of a gas discharging 10 device adapted to operate when the walls of the vault are attacked, to disseminate noxious gas on the interior of the vault and prevent access thereto, even though an opening in the wall may be made.

15 It is also a purpose of the invention to provide a protecting device of this type which will be of extremely sensitive character and adapted to operate regardless of the position of attack, or the force employed.

20 Other objects and advantages of the invention will be apparent as it is better understood from the following description, which, taken in connection with the accompanying drawings, discloses a preferred embodiment 25 thereof.

Referring to the drawings,

Figure 1 is an interior perspective view of a portion of a vault in which a protecting system embodying my invention is installed; 30 Fig. 2 is an elevational view of a portion of the outer wall of the vault, showing the means by which the force of attack is utilized to operate the gas discharging device;

Fig. 3 is a transverse section taken substantially on the line 3—3 in Fig. 2;

Fig. 4 is an enlarged vertical section, taken through the bomb receptacle and bolt sleeve;

Fig. 5 is a detailed view, partially in section, of the bolt releasing mechanism; and

Fig. 6 is a top plan view of the parts shown in Fig. 5.

Upon the drawings, the main wall of the vault is indicated by the reference character 11 and the character 12 indicates an inner wall which is spaced from the main wall by suitable spacing members 13 and 14.

A box, or casing, 15 is positioned on the interior of the wall part 12 and contains a gas receptacle 16, which preferably is of glass, or other material adapted to be easily broken.

As shown, the gas receptacle is of segmental form and a ball 17 is positioned between the segments and in position to be struck by a plunger 18 when the latter is projected by a spring 19. Said plunger is normally held retracted and under the tension of the spring 19 by means of a flexible connection 21, secured to the upper end of an extension rod 22 upon which said spring is mounted. Said plunger and spring are enclosed in a sleeve 23, which has upper shoulders 24 against which the spring engages. A slide 25 is provided in the top of the box 15 and has an aperture through which the plunger 18 may extend when the slide is in proper position. Said 55 slide is provided also with slots 26 through which guiding screws 27 extend and it will be manifest that when said slide is in its outer position, the system will be rendered inoperative, since the plunger will be prevented 60 from breaking the receptacle. The connection 21 extends over a sheave which is positioned in a block 28 and is connected at its opposite end to a rod 29 which is housed in a sleeve 31. Said sleeve has one end secured 65 in a block 32, which is apertured to permit the rod 29 to move therethrough. Said rod is provided with a cut-out 33 adapted to be engaged by an arm 34 of a lever 35, said arm being normally held in engagement with the 70 rod by means of a spring 36 which is positioned in the block 32. Said lever is adapted to be operated to disengage the rod 29 by means of a trip lever 37, which is mounted 75 for actuating the lever 35, an arm of which 80 extends through the wall part 12. Said lever 37 is operable by means to be now described.

Said trip lever 37 is operated by a connection 38, which extends about a sheave 39 and is secured to a ring 41. Said ring is connected 90 by means of a plurality of wires, or other flexible connections, 42 with the opposite ends of yokes 43, the latter being of whiffletree type, being pivoted at a central point 44 to a plate 45 extending out from the wall spacing member 13. Said yokes, or whiffletrrees, 43 are operated by means of a plurality of wires, or cords, arranged at close intervals about the walls of the vault to operate the trip lever 37.

It will be noted that these connections are arranged in the floor and ceiling, as well as on the side walls and they may be briefly traced as follows. Referring to Fig. 2, it will be seen that a connection 46 is secured at 47 to one of the yokes and extends around sheaves 48 at the bottom of the wall and similar sheaves 49 at the top, being directed up and down at relatively close intervals in this manner. Another connection 51 is connected at 52 to another yoke 43 and extends about sheaves 53 and 54 whereby it is directed over the area of the plate 45 and thence over a sheave 55 and about the ceiling in manner similar to the arrangement of the connection 46 about the side wall. Channel members 56 are provided about the ceiling and said connection 51 extends therethrough and around suitable rollers, or guides, 57 at the ends of said members.

Another connection 58 is secured at 59 to one of the members 43 and extends down about a sheave 61 and is directed over the floor through channel members 62, corresponding to the members 56 on the ceiling. A fourth connection 63 is secured at 64 to a fourth member 43 and it extends about sheaves 65, 66 and 67 to the side wall, shown at the left in Fig. 2, and it will be understood that these connections may be extended, as desired, to cover any wall arrangement. Springs 68 are provided for each of the members 43, being connected thereto at the end opposite that to which the wires are connected and having their opposite ends secured as at 69 to the plate 45. It will thus be evident that if one of the wall protecting connections is pulled or stretched by an attack on the wall, the side of the whiffletree 43 to which it is attached will be drawn down and the ring 41 moved therewith, thus operating the lever 37 and permitting the spring 19 to project the plunger 18 to discharge the gas. If, on the other hand, the connection be broken, one of the springs 68 will pull the opposite end of the member 43 downwardly with similar result. Thus an attack at any point, either in the wall, the ceiling, or the floor will result in a discharge of noxious gas into the interior of the vault, rendering the same inaccessible and the burglar will be foiled, even though his attack may have resulted in providing an opening through which he might otherwise enter.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A vault protecting system, comprising a gas receptacle positioned on the interior of the vault, normally inoperative means for causing discharge of the contents of said receptacle, a flexible connection extending about the fixed walls of the vault, and devices operable by either release or pulling of said connection to cause operation of said gas discharging means, said devices comprising members of whiffletree form having one end held under spring tension and the other end held by said flexible connection, and means operable by pivotal movement of said members for causing operation of said gas discharging means. 70 75 80

2. In a vault protecting device, the combination of a vault, an actuatable device for releasing gas into said vault, a plurality of pivotal members in said vault, a spring connected to each pivotal member and arranged to swing the pivotal member in one direction, a plurality of said wall protecting members, each disposed in network formation over a particular wall portion of the vault, said members being arranged to cover substantially all of the wall portions of the vault, each one of said members being connected to an individual pivotal member to the end thereof opposite the spring connected end and constructed and arranged to hold such member from being swung under the influence of the spring, a spring actuated trigger mechanism for actuating the gas releasing device and a plurality of connections, one from each end of the pivotal members to said trigger mechanism, whereby said trigger mechanism is actuated by a severance or movement of any of the protective devices. 90 95 100

3. A vault protecting device, in combination with a vault, a gas release therefor, a trigger mechanism for actuating said gas release, a flexible member extending across the wall portion of the vault, a pivoted arm, a tension spring connected to one end of the pivoted arm, a flexible member connecting such end of the pivoted arm to a trigger mechanism, a second flexible member connected to the opposite end of the pivotal member and to the trigger mechanism, said flexible member, which extends across the vault, being connected to the last mentioned end of the pivoted member, whereby the trigger mechanism is actuated either by a pulling upon the flexible member or by severance of the flexible member. 110 115 120

4. A vault protecting device, comprising a frangible gas receptacle located within said vault, a receptacle breaking member, a spring for forcing said breaking member toward said receptacle to rupture the latter, means for holding said breaking member in a position under the influence of said spring, a trigger mechanism connected to said latter means and devices constructed and arranged 125 130

to be actuated by an attempted forcible entry into said vault for releasing said trigger mechanism to permit the projection of the breaking member against said receptacle, 5 whereby to release the gas.

5. A vault protecting device, comprising a container adapted to receive a plurality of segmental frangible gas containers, a metal ball disposed above and intermediate said 10 gas containers and in contact therewith, a plunger located immediately above said ball, a spring for projecting said plunger into contact with said ball to break said gas containers, means for holding said spring 15 under compression and devices constructed and arranged to be actuated by an attempted forcible entry into said vault or by releasing said spring, whereby to release the gases within the vault.
